UNITED STATES PATENT OFFICE

2,542,151

BUILDING CONSTRUCTION

John H. McAuliffe, Jr., Oak Park, Ill.

Application June 6, 1947, Serial No. 752,927

3 Claims. (Cl. 20—2)

1

The present invention relates to a building construction and more particularly a construction for a building composed of rigid wooden frames, the parts of which may be prefabricated and packaged at a central plant and shipped to the site of the building where they may then be attached together either by means of waterproof glue alone or by a combination of waterproof glue and a minimum of nails, screws or other fastening means.

The object of the invention is to provide a rigid frame sectional building in which complete freedom is afforded the builder in the placing of interior partitions and other types of division.

Another object of the invention is to provide a rigid frame sectional building which may be pre-cut to specifications and thereby more expeditiously shipped and erected.

Another object is to provide a structural method or system which, through standardization of basic structural shapes and use of a standard module, permits innumerable variations in the application of standard sized doors, windows, and exterior and interior finish.

Another object of the invention is to provide a rigid frame sectional building in which the parts may be provided with notches for attachment to adjoining sections and by means of strengthening members such as gussets bonded to adjoining sections by waterproof glue alone or by a combination of waterproof glue and a minimum of nails, screws or other fastening means.

Another object of the invention is to provide a construction having a strengthening or connecting member or ribband for the studs and roof supporting members and which provides a natural base for continuous cove lighting along said ribband, and which may be adapted for clerestory lighting at the intersection of the rafters where secured by gussets.

Other objects of the invention will be readily apparent from the drawing, in which:

Figure 1 is an end view of a building constructed in accordance with the invention;

Figure 2 is an enlarged view partly in section on the line 2—2 of Figure 4;

Figure 3 is a sectional view taken on the line 3—3 of Figure 2;

Figure 4 is an enlarged fragmentary top plan view partly in section of the outer end of the roof;

Figure 5 is a fragmentary perspective view of the ribband or roof and stud connection member; and

2

Figure 6 is a fragmentary perspective view of the roof ridge.

While my invention is susceptible of embodiment in many different forms, I have shown in the drawings and will herein describe in detail one such embodiment, with the understanding that the present disclosure is to be considered as an exemplification of the principles of the invention and is not intended to limit the invention to the embodiment illustrated. The scope of the invention will be pointed out in the appended claims.

Referring to the drawing the building constructed in accordance with the invention is shown as comprising a plurality of studs 10 which may be two by fours or two by sixes of the desired height and extend upwardly from a support such as a floor sill 11 mounted in or on a suitable base such as a concrete floor, notches having been previously cut in the sill at suitably spaced intervals to receive the lower ends of the studs. At their upper ends the studs are received in transverse notches 12 in an upper support member or ribband 13, this member also being provided with notches 14 in its upper side for the reception of a rafter 15 or 15a, each of said rafters also resting on and being supported by the top of a stud 10, the top being cut at the proper angle as shown in Figure 2.

Near their inner ends the rafters 15 and 15a are secured to plywood gussets 16. Ridge board 17 is attached to the rafter ends. Ridge member 18 consists of solid bridging secured to the rafters along the edge of the plywood gussets. As shown in Figure 1 the gussets 16 are of triangular shape, the upper angle of the triangle being flush with the end of one rafter 15. As shown in the drawings, the gusset is an isosceles triangle with its base on a vertical line, the two edges of the base being the ridge board 17 and solid bridging 18. The apex of the triangle is on the edge of the rafter 15. The rafter 15a is cut at an angle to support the other edge of the rafter 15. Each rafter set, 15 and 15a, is preferably provided with two gussets 16, one on each side, and the gussets are attached to the rafters by means of waterproof glue, or a combination of waterproof glue and a minimum of nails, screws, or other fastening means. In the variation shown on the drawing, the rafter 15 is longer than the rafter 15a so that the two rafters will meet at the center line between the two sets of studs 10 but could meet in conventional manner at such line. The space between the boards 17 and 18 may be

closed by siding or the like or may be left open or be closed by louvers to permit ventilation.

At their outer ends the rafters are also provided with triangular shaped gussets 19 which are right angles having a blunt end to which is secured the eave board 20, the gussets 19 being secured to the upper sides of the studs 10 and the rafter 15 or 15a by either waterproof glue or a combination of waterproof glue and a minimum of nails, screws or other fastening means, there being preferably two gussets one on each side.

It is apparent from the above description that the invention provides a rigid frame structure that eliminates the necessity for the usual ceiling joists or horizontal beams extending from the tops of opposing rafters. The construction furthermore dispenses with the necessity for any interior bearing walls, and permits of a minimum of nails, screws, bolts and the like; the waterproof glue alone is sufficient, although field conditions may require the use of a minimum of nails, screws, or other fastening means to insure proper alignment of the members and bonding of the glue. Windows, doors and exterior and interior finish may be placed as desired without the necessity for any rough framing, and the use of glue may replace the usual metal joining elements. Likewise the structure permits the placement of interior partitions at substantially any desired part of the structure, since such partitions would all be non-bearing. The ribband or support member is of sufficient strength to permit elimination of certain studs thus affording larger clear openings for windows, doors or the like.

I claim:

1. In a rigid frame structural construction, base members, a pair of opposed rows of vertical

studs supported on and extending upwardly from the base members, a rafter extending upwardly and inwardly from each of said studs and resting on and in coplanar relation thereto and extending outwardly and downwardly therefrom, a triangular gusset secured to the side face of the outer end of each rafter and the upper end of its supporting stud, a structural member extending along the studs of each row and secured to their inner faces at the top and supporting the rafters of one row, the rafters of one row being in coplanar relation to those of the other row and abutting against the under sides thereof substantially short of their upper ends and a triangular gusset plate secured to the sides of engaging ends of each pair of rafters for securing them together.

2. The structure set forth in claim 1 wherein the studs and said structural members are joined by notches in said members.

3. The structure set forth in claim 1 wherein the joining means for the gussets is waterproof glue.

JOHN H. McAULIFFE, JR.
